CLEANING AND POLISHING DEVICE

Leslie A. Tyler, Dunmore, Pa.

Application November 5, 1936, Serial No. 109,397

3 Claims. (Cl. 15—230)

The present invention relates to cleaning and polishing devices particularly designed for telephone and telegraph jack cleaning purposes.

The primary object of the invention is to provide a simple, inexpensive, durable and efficient device for cleaning and polishing telephone jacks, the device adapted to be used with any ordinary hand drill or similar tool.

A further object of the invention is to provide a cleaning and polishing device of the character stated that is adjustable for cleaning any standard size telephone or telegraph jack mounted on a panel of any thickness.

A still further object of the invention resides in the provision of a cleaning and polishing element supported over one end of a shaft intermediate its ends and the ends secured to a flanged nut that is rotatable on the shaft.

The invention will be fully and comprehensively understood from a consideration of the following detailed description when read in connection with the accompanying drawing which forms part of the application.

In the drawing:

Fig. 1 is a perspective view of the cleaning and polishing device assembled for use.

Fig. 2 is an end elevational view of the device shown in Fig. 1.

Fig. 3 is a transverse sectional view thru the device.

Fig. 4 is a vertical sectional view taken on line 4—4 of Fig. 3.

Fig. 5 is an exploded perspective view of the flange and lock nuts respectively; and

Fig. 6 is a perspective view of the clip for securing the cleaning element upon the flanged nut.

Referring to the drawing for a more detailed description thereof, the numeral 8 indicates a shaft formed of tool steel, brass or any similar hard substance, which is threaded intermediate its ends as at 9 for the reception of the flanged nut 10 and lock nut 11, the purpose of which will be hereinafter described.

The end of the shaft 8 is provided with transverse intersecting grooves 12 and 13 within which the flexible cleaning and polishing element 14 is positioned for cleaning a telephone jack or the like. The cleaning element 14 may be formed of any desired soft, flexible material such as cord or string and is supported on the shaft 8 by means of the flange nut 10, said nut being provided with a series of grooves 15 on the periphery thereof through which the flexible cleaning element is threaded. For retaining the cleaning element

14 within the grooves 15 there are provided spring clips 16, one end thereof being positioned within a recess 17 and the curved end 18 supported in an opening 19 provided in the flanged portion 10 of the nut 10. The ends of the cleaning element 5 are clamped in the spring portion of the clip 16 and said clips serve the further purpose of maintaining the proper tension on the cleaning element. The said clips are rigidly fastened to the flanged nut by soldering in the position illustrated in Fig. 3 of the drawing.

When using the device for cleaning a telephone jack, the outside of the jack is first moistened with a liquid cleaner. The free end of the shaft 8 is positioned within a chuck 20 of a rotary 15 tool, the forward or entering end of the shaft 8 is inserted into the jack until it touches the extreme end of the jack. The flanged nut 10, which has been positioned towards the free end of the shaft, is then rotated so as to be in contact with the outside face of the jack after which the lock nut 11 is locked against flanged nut 10 to prevent its further movement on shaft. After obtaining the proper adjustment of the flanged nut 10, the device is prepared for work by the 20 attachment of the cleaning element in the following manner.

One end of the string or the cleaning element is positioned within one of the spring clips 16 and is then wound thru the groove closest to the clip and then into one of the intersecting grooves 12 or 13. Continued winding of the string places it into another groove 15 and clips 16 on the opposite side, then into the next adjacent clip not previously used and then successively thru intersecting grooves 13 and 15 and 25 into the remaining clip after which the cleaning element may be severed. The above operations 30 are very simple and are performed in a few seconds and the positioning of the cleaning element is accomplished in a manner similar to the winding of a string on a spinning top. The device is then positioned within the jack and rotated thru the rotary tool. A few rotations of the drill will thoroughly clean the jack and the operation may be repeated as often as desired. After cleaning 40 several jacks new cleaning elements are applied and polish added, after which the cleaner serves also as a polisher by rotating the tool as above indicated. The cleaning element 14 may be replaced as often as desired, which operation is a 45 simple one and is accomplished as described above.

The flanged nut 10 is provided with a raised ring 21 for the purpose of cleaning indentations in the face of the ordinary jack. This nut is in 55

contact with the face of the jack during the entire cleaning or polishing process and prevents tip of shaft 8 from bearing too hard on the inside of the jack. The said flanged nut 10 is adjustable on the threads 9 of the shaft 8 so that the forward or entering end of the shaft 8 containing the cleaning element may be lengthened or shortened so as to clean or polish the entire length of the jack at the same time cleaning or polishing the face of the jack. This feature enables the one device to clean jacks mounted on panels of any thickness. The lock nut 11 serves the purpose of locking the flanged nut 10 into place thus maintaining the desired length of the forward end of the shaft 8.

It is to be understood that this improvement is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed as new is:

1. A cleaning and polishing device of the character described, comprising a shaft threaded intermediate its ends, one end face of said shaft having transverse slots for receiving a flexible cleaning and polishing element, a flanged nut mounted for rotation on the threaded portion of said shaft, means within said flanged nut for receiving the flexible cleaning and polishing ele-

ment, said means comprising clip-like members carried by the periphery of said nut, and means carried by said shaft for locking said nut.

2. A cleaning and polishing device of the character described, comprising a shaft threaded intermediate its ends, one end face of said shaft having transverse slots for receiving a flexible cleaning and polishing element, a flanged nut mounted for rotation on the threaded portion of said shaft, means within said flanged nut for receiving the flexible cleaning and polishing element, said means comprising spaced clips supported in grooves in the body portion of said nut, and means for adjusting the device by means of the flanged nut so as to clean the entire depth of jack at the same time cleaning the face thereof.

3. A cleaning and polishing device of the character described, comprising a shaft threaded intermediate its ends, one end face of said shaft having transverse slots for receiving a flexible cleaning and polishing element, a flanged nut mounted for rotation on the threaded portion of said shaft, a raised cleaning ring formed on the front face of said nut for facilitating pressing a cleaning element against an annular surface to be cleaned, means within said flanged nut for receiving the flexible cleaning and polishing element, said means comprising clip-like members carried by the periphery of said nut, and means carried by said shaft for locking said nut.
